CLAIM

The ornamental design for a chart recorder door, as shown.

DESCRIPTION

FIG. 1 is a top, front and left side perspective view of a chart recorder door showing our new design;

FIG. 2 is a front elevational view thereof;

FIG. 3 is a top plan view thereof;

FIG. 4 is a left side elevational view thereof;

FIG. 5 is a right side elevational view thereof; and,

FIG. 6 is a bottom plan view thereof.

The broken line showing of a chart recorder housing is for environmental purposes only and forms no part of the claimed design.
